UNITED STATES PATENT OFFICE.

NANCY D'WOLF CLARK, OF GLEN HEAD, AND ALMA B. ARMSTRONG, OF NEW YORK,
N. Y., ASSIGNORS TO THE AMERICAN NATIONAL RED CROSS, A CORPORATION.

PROCESS OF BRAILLE TRANSCRIPTION.

No Drawing.

Application filed December 24, 1925. Serial No. 77,616.

Our present invention pertains to Braille transcriptions and it contemplates the provision of a simple and inexpensive process through the medium of which a large number of copies of Braille transcriptions may be readily and easily produced.

In using our invention we employ the ordinary well known perforation of Braille writing comprising the use of a thin sharp point preferably of the construction required by the Hall Braille writer which is employed for transcribing and it is also necessary to use oiled Cromwell bond paper or the equivalent for embossing.

A matrix formed in any manner desired is employed for the duplicating work and in conjunction therewith we use a folder approximately twelve by seventeen inches in size to receive the matrix and said folder consists of two pieces of pressed board, one piece of stamping rubber of approximately one-quarter inch in thickness and of dimensions similar to those of the two pieces of pressed board. On one side of this stamping rubber we paste a piece of muslin and fasten the two pieces of pressed boards and rubber together with the rubber in the center and having one end provided with a narrow binding.

The matrix is then placed in this folder and the printing or reproducing operation is in order and is accomplished by thoroughly wetting from one to five hundred sheets of paper and placing same on

top of each other. Care must be taken to wet each sheet separately. The sheets are then laid between boards with a heavy weight placed on top of the boards and this must be done at least twenty-four hours before printing or reproducing is started. The sheets are then removed from the boards and placed between blotters; each sheet separately and blotted so that the paper will be thoroughly damp but not shiny with moisture. The sheets are then placed on the rubber in the folder and the matrix is placed on top of the sheets. It is to be understood that the matrix as is customary is provided with an embossed or dot side and this embossed side is placed on top of the sheets with the embossed surface down and the folder is then run through a press.

We claim:

The process of producing Braille writing consisting of inserting a piece of stamping rubber backed with muslin in a folder formed of two pieces of pressed board, and then placing slightly saturated pieces of paper in to the folder against the rubber and placing a matrix on top of the paper with the embossed side down and running the folder between pressure rollers.

In testimony whereof we have hereunto set our hands.

NANCY D'WOLF CLARK.
ALMA B. ARMSTRONG.
